UNITED STATES PATENT OFFICE

EDWARD E. CLARK, OF LOS ANGELES, CALIFORNIA, ASSIGNOR TO GEORGE S. LEWIN, OF SANTA MONICA, CALIFORNIA

HOLSTER

Application filed October 14, 1931. Serial No. 568,773.

This invention relates to improvements in holsters for firearms and the like.

An object of the invention is to provide a forward thrust holster adapted to carry a firearm or other suitable implement which is so designed as to facilitate easy and quick removal of the firearm from the holster, enabling a quick "draw".

In detail an object of the invention is to provide a holster for firearms and the like comprising a holster body adapted to receive the firearm, which holster has an open side normally closed by a yieldable barrier which normally retains the firearm within the holster but which permits it to be quickly removed from the holster through the open side into firing position.

Another object of the invention is to provide an improved holster construction which is of relatively simple design and which may be easily manufactured.

With the foregoing and other objects in view, which will be made manifest in the following detailed description, and specifically pointed out in the appended claims, reference is had to the accompanying drawing for an illustrative embodiment of the invention, wherein:

Fig. 1 is a partial view in elevation illustrating the improved holster in applied position and illustrating in dotted lines the manner in which the firearm may be quickly withdrawn and moved into firing position.

Fig. 2 is a larger view in side elevation of the improved holster, parts being broken away and shown in vertical section.

Fig. 3 is a view in elevation of the holster taken in the direction of the arrow 3 upon Figure 2.

Fig. 4 is a sectional view taken substantially upon the line 4-4 upon Figure 2.

Fig. 5 is a partial view in side elevation illustrating a slightly modified form of construction.

Fig. 6 is a sectional view taken substantially upon the line 6-6 upon Figure 6.

Referring to the accompanying drawing, wherein similar reference characters designate similar parts throughout, I have illustrated the holster as being designed to be

worn at the belt and to carry a revolver. The holster consists of a holster body formed of leather or any other suitable material shaped to snugly receive a revolver R. The body has sides 10 and 11 connected together as by stitching 12 to form a back 13. These sides are also connected at the bottom to provide a bottom for the holster indicated at 14. At the forward side of the holster the sides 10 and 11 are unconnected and have spaced side edges 15 and 16 defining an open forward side of the holster body. Along these side edges 15 and 16 there may be projecting tabs 17 and 18. The upper pair of tabs is arranged near the top of the holster and the lower pair of tabs is arranged near the bottom of the holster. Spring clips 20 and 21 encircle the holster and have adjacent forward ends 22 and 23 which, by the resiliency of the springs, are urged toward each other across the open side of the holster. These spring clips may be secured to the body of the holster by protective leather coverings or straps 24 secured in place by suitable stitching 25. It will thus be seen that the ends 22 and 23 of the spring clips are leather covered and are urged toward each other to form a barrier across the open forward side of the holster. These ends forming this barrier serve to maintain the revolver R within the holster. Whenever it is desired to quickly remove the revolver from the holster, its handle may be grasped and the revolver moved bodily forward. This pressure of the revolver between the ends of the spring clips causes the ends of the spring clips to separate, allowing the revolver to slide therethrough and thus permitting it to be quickly moved into the firing position shown in dotted lines upon Figure 1.

It will thus be appreciated that by the improved holster the revolver R can be quickly withdrawn therefrom with a minimum amount of effort and a minimum amount of manipulation bringing it into firing position. In the case of revolver holsters I prefer to have the body of the holster secured to a belt B as by stitching 26. It will be readily appreciated, however, that the application of the invention is not restricted to belt type

revolver holsters but may likewise be applied to rifle scabbards and even to knife holsters.

In the modification shown in Figure 5 the body of the holster, generally designated at 30, has its inner side wall provided with an extension 31 constituting a cover flap. The fold line for this cover flap is indicated by the dotted line 32 and the cover flap is designed to be folded over the top of the holster 10 over the firearm or weapon positioned therein. On the interior of the cover flap there are positioned springs, these being shown as being formed of a pair of coil springs 33 and 34. Any other suitable spring could be 15 employed if desired. These springs extend across the fold line 32 and are enclosed within a cover strip 35 of leather or equivalent material which has its side edges stitched as at 36 to the inner side of the cover flap. 20 The springs may be held separated from each other by stitching 37. The cover flap may be normally held in closing or covering position by means of a suitable snap fastener, parts of which are indicated at 38. Any 25 equivalent construction for holding the cover flap closed may be employed if desired. In operation of this construction loosening of the cover flap or separation of the parts 38 of the fastener enables the springs 33 and 30 34 to become effective to swing the cover flap open. A forward thrust of the firearm or weapon in the holster will cause it to move bodily through the open forward side of the holster, as previously described.

35 In all constructions the weapon retained within the holster may be removed therefrom by a simple forward thrust which can be easily and quickly accomplished by a forward swinging movement of the wearer's arm. 40 Various changes may be made in the details of construction without departing from the spirit or scope of the invention as defined by the appended claims.

I claim:

- 45 1. A holster for firearms and the like comprising a holster body adapted to receive a firearm, that side of the body against which the top of the barrel of the firearm is adapted to be positioned being open to permit the 50 firearm to be moved therethrough, and means forming a barrier over the opening for normally retaining the firearm within the holster.
- 55 2. A holster for firearms and the like comprising a holster body adapted to receive a firearm, the front side of the body being open from top to bottom to permit the firearm to be moved forwardly therethrough, and yieldable means forming a temporary barrier over 60 the opening for normally retaining the firearm within the holster.
- 65 3. A holster for firearms and the like comprising a holster body having a forward open side against which the top of the barrel of a firearm is adapted to be positioned, and

spring means urging portions of the holster adjacent the open side toward each other forming a yieldable barrier for normally retaining a firearm in the holster.

4. A holster for firearms and the like comprising a holster body adapted to receive a firearm, said holster having a forward side which is open from top to bottom to permit the firearm to be moved forwardly, and springs secured to the holster having ends urged toward each other across the open side forming a yieldable barrier normally holding the firearm within the holster. 70

5. A holster for firearms and the like comprising a holster body adapted to receive a firearm, said body having an open forward side extending the complete length of the holster, springs secured to the holster and encircling it, said springs having adjacent ends urged together across the open forward 80 side forming a yieldable barrier normally retaining the firearm within the holster. 85

6. A holster for firearms and the like comprising a holster body adapted to receive a firearm, the front side of the body against which the top of the barrel of the firearm is adapted to be positioned being open to permit the firearm to be moved barrel first forwardly therethrough, means forming a barrier over the opening for normally retaining the firearm within the holster, and a cover flap for the holster. 90

7. A holster for firearms and the like comprising a holster body adapted to receive a firearm, one side of the body being open to permit the firearm to be moved therethrough, means forming a barrier over the opening for normally retaining the firearm within the holster, a cover flap for the holster, said cover flap being provided with spring means 100 normally urging it into open position, and means for holding the cover flap in closed position against the action of said spring means. 105

In testimony whereof I have signed my name to this specification.

EDWARD E. CLARK.
